(57) **CLAIM**

The ornamental design for a spinning insert polishing pad, as shown and described.

DESCRIPTION

FIG. 1 is a top perspective view of the spinning insert polishing pad showing my new design;

FIG. 2 is a bottom perspective view of the spinning insert polishing pad showing my new design;

FIG. 3 is a top plan view of the spinning insert polishing pad showing my new design;

FIG. 4 is a bottom plan view of the spinning insert polishing pad showing my new design;

FIG. 5 is a front elevation view of the spinning insert polishing pad showing my new design;

FIG. 6 is a rear elevation view of the spinning insert polishing pad showing my new design; and

FIG. 7 is a right side view of the spinning insert polishing pad showing my new design; and,

FIG. 8 is a left side view of the spinning insert polishing pad showing my new design.

The stippling on the upper surface is meant to represent a pattern that extends uniformly across the entire surface.
